FENDER ORNAMENT FOR AUTOMOBILES OR THE LIKE

Eugene Bordinat, Jr., Bloomfield Hills, Mich., assignor to
The Ford Motor Company, Dearborn, Mich., a corporation of Delaware

Filed Oct. 13, 1961, Ser. No. 67,066

Term of patent 7 years

(Cl. D14—6)

FIG. 3.

FIG. 5.

FIG. 1.

FIGURES 5, 6 and 7 are sectional views taken on the planes indicated by the lines 5-5, 6-6 and 7-7, respectively, of FIGURE 2.

I claim:

The ornamental design for a fender ornament for automobiles or the like, substantially as shown.
